Primary Examiner — Sharon S Oum*(74) Attorney, Agent, or Firm* — Dickinson Wright PLLC**CLAIM**

I claim the ornamental design for an evaporative air cooling tower, as shown and described.

DESCRIPTION

FIG. 1 is a top-front perspective view of an evaporative air cooling tower;

FIG. 2 is a front view of the evaporative air cooling tower of FIG. 1;

FIG. 3 is a rear view of the evaporative air cooling tower of FIG. 1;

FIG. 4 is a left side view of the evaporative air cooling tower of FIG. 1;

FIG. 5 is a right side view of the evaporative air cooling tower of FIG. 1;

FIG. 6 is a top view of the evaporative air cooling tower of FIG. 1;

FIG. 7 is a bottom view of the evaporative air cooling tower of FIGS. 1; and,

FIG. 8 is a top-rear perspective view of FIG. 1.

The broken lines in the drawings illustrate portions of the evaporative air cooling tower that form no part of the claimed design.
